US00D886606S

(12) **United States Design Patent** (10) **Patent No.:** **US D886,606 S**
(45) **Date of Patent:** ** *Jun. 9, 2020

(54) **PACKAGING COMPONENT**

- (71) Applicant: **Apple Inc.**, Cupertino, CA (US)
- (72) Inventors: **Jody Akana**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)
- (73) Assignee: **Apple Inc.**, Cupertino, CA (US)

(*) Notice: This patent is subject to a terminal disclaimer.

(**) Term: **15 Years**

(21) Appl. No.: **29/664,790**

(22) Filed: **Sep. 27, 2018**

(57) **CLAIM**

The ornamental design for a packaging component, as shown and described.

DESCRIPTION

FIG. 1 is a top front perspective view of a packaging component showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

(Continued)

FIG. 8 is a top view thereof showing the packaging component in an environment in which it may be used. The broken lines in the figures show portions of the packaging component or environment that form no part of the claimed design.

The figures are illustrated to show contrasting appearance. The portions shown in light gray have one appearance, and the portions shown in darker medium gray have a second appearance.

1 Claim, 5 Drawing Sheets

Related U.S. Application Data

continuation of application No. 29/571,608, filed on Jul. 20, 2016, now Pat. No. Des. 792,768, which is a continuation of application No. 29/500,899, filed on Aug. 29, 2014, now Pat. No. Des. 764,910.
